his ATTORNEY

UNITED STATES PATENT OFFICE

LOUIS TARTAZ, OF NEW YORK, N. Y.

BUNSEN-BURNER ATTACHMENT

Application filed January 18, 1930. Serial No. 421,806.

The object of my invention is to provide a simple, practical and inexpensive contrivance to be attached to an ordinary Bunsen burner for performing operations needful and finding particular utility in dental, chemical, jewelry and manufacturing trades; in particular for the elimination of wax from dental investments and other small castings, and also to provide a means for evenly heating minerals, laboratory specimens and articles of jewelry.

A further object of this invention is to provide flame deflectors to resist the tendency of the flame to rise upwards, and to guide the flame more surely, effectively and directly against the article to be heated.

The preferred embodiment of my invention comprises a funnel-shaped gas chamber, the nipple of which is set onto the nozzle of a Bunsen burner, and the top of which is closed and sealed by a cap member which is provided with orifices around its inner wall to produce a series of radially, inwardly horizontal flames guided by deflector lugs onto a platform centrally positioned, whereon is placed the dental investment or article to be heated. The wax, if there be any as a component of the article heated, when molten by the heat of the flames, flows off said platform in sluices therein provided into a trough in said cap member, and is drained off through a pipe connected with said trough.

In the accompanying drawings, forming a part of this application, similar characters of reference indicate corresponding parts in all the views.

Figure 1, shows my invention attached to a Bunsen burner.

Figure 2, is a top view of my present invention.

Figure 3, is a vertical cross-section of my invention, at line 3-3 in Figure 2.

Referring to the drawings, 4 is a sheet metal or cast, circular funnel-shaped gas chamber, the nipple 5 of which sets onto nozzle 6 of a Bunsen burner 7, and the top of which is closed and sealed by cap member 8. Cap member 8 is shaped so as to form and include a vertical wall 9, a trough 10,

and a horizontal platform 11. Wall 9 is provided with a series of equidistant, radially discharging orifices 12, each of which orifice is provided with a deflector lug 13. Platform 11 is provided with a series of 55 sluices 14. To trough 10 is connected a drain pipe 15.

I claim:

1. In an attachment of the character described, a gas chamber adapted to set onto the nozzle of a Bunsen burner, a cap member securely sealing said chamber, being comprised of a platform and a wall forming a trough therebetween, said wall being spaced from said chamber, and having a series of 60 radially, horizontally discharging orifices.

2. In an attachment of the character described, a funnel-shaped gas chamber, the nipple of which is adapted to set onto the nozzle of a Bunsen burner, a cap member 70 securely sealing said chamber, being comprised of a platform and a vertical wall forming a trough therebetween, said wall being spaced from said gas chamber and having a series of radially, horizontally discharging 75 orifices.

3. In an attachment of the character described, a funnel-shaped gas chamber, the nipple of which is adapted to set onto the nozzle of a Bunsen burner, a cap member 80 securely sealing said gas chamber, being comprised of a platform and a vertical wall forming a trough therebetween, said platform having sluices and said wall being spaced from said gas chamber and having a series 85 of radially, horizontally discharging orifices.

4. In an attachment of the character described, a funnel-shaped gas chamber, the nipple of which is adapted to set onto the nozzle of a Bunsen burner, a cap member 90 securely sealing said gas chamber, being comprised of a platform and a vertical wall forming a trough therebetween, a drain pipe connected to said trough, said platform having sluices, and said wall being spaced from said 95 gas chamber and having a series of radially, horizontally discharging orifices.

5. In an attachment of the character described, a funnel-shaped gas chamber, the nipple of which is adapted to set onto the 100

nozzle of a Bunsen burner, a cap member securely sealing said gas chamber, being comprised of a platform and a vertical wall forming a trough therebetween, a drain pipe connected to said trough, said platform having sluices, and said wall being spaced from said gas chamber and having a series of radially, horizontally discharging orifices, and flame deflector lugs protruding from said wall, one over each of said orifices.

6. In an attachment of the character described, a funnel-shaped gas chamber, the nipple of which is adapted to set onto the nozzle of a Bunsen burner, a cap member securely sealing said gas chamber, being comprised of a platform and a vertical wall forming a trough therebetween, said platform having sluices, and said wall being spaced from the gas chamber and having a series of radially, horizontally discharging orifices, and flame deflector lugs protruding from said wall, one over each of said orifices.

7. In an attachment of the character described, a funnel-shaped gas chamber, the nipple of which is adapted to set onto the nozzle of a Bunsen burner, a cap member securely sealing said gas chamber, being comprised of a platform, and a vertical wall forming a trough therebetween, said wall being spaced from said gas chamber and having a series of radially, horizontally discharging orifices, and flame deflector lugs protruding from said wall, one over each of said orifices.

8. In an attachment of the character described, a funnel-shaped gas chamber, the nipple of which is adapted to set onto the nozzle of a Bunsen burner, a cap member securely sealing said gas chamber, being comprised of a horizontal platform and a substantially vertical wall forming a trough therebetween, said trough surrounding said platform, and said wall being spaced from said gas chamber and having a series of radially, horizontally discharging orifices, and flame deflector lugs protruding from said wall, one over each of said orifices.

9. In an attachment of the character described, a funnel-shaped gas chamber, the nipple of which is adapted to set onto the nozzle of a Bunsen burner, a cap member securely sealing said gas chamber, being comprised of a centrally placed horizontal platform, and a trough surrounding said platform, a drain pipe connected to said trough and the wall of the trough which is farthest from the platform, being provided with a series of radially, horizontally discharging orifices, and flame deflector lugs protruding from said wall, one over each of said orifices.

10. In an attachment of the character described, a circular funnel-shaped gas chamber, the nipple of which is adapted to set onto the nozzle of a Bunsen burner, a circular cap member securely sealing said gas chamber, being comprised of a circular, centrally

placed horizontal platform and a substantially cylindrical wall surrounding said platform forming a trough therebetween, a drain pipe connected to said trough, said platform having sluices and said wall being spaced from said gas chamber and being provided with a series of radially, horizontally discharging orifices, and flame deflector lugs protruding from said wall, one over each of said orifices.

In witness whereof, I affix my signature.
LOUIS TARTAZ.
